(57) **CLAIM**

The ornamental design for a extruded rail set used for mounting solar panels, as shown and described.

DESCRIPTION

FIG. 1 is a right side elevation view of a set of extruded rails;
FIG. 2 is a front and right side perspective view;
FIG. 3 is a back and right side perspective view;
FIG. 4 is a left side elevation view;
FIG. 5 is a top plan view; and,
FIG. 6 is a bottom plan view.

The set of extruded rails in FIGS. 2-3 and 5-6 have been broken in the center to indicate indefinite length.
